US00D825543S

(12) **United States Design Patent** (10) **Patent No.:** **US D825,543 S**
(45) **Date of Patent:** **** Aug. 14, 2018**

- (54) **CASE FOR ELECTRONIC DEVICES**
(71) Applicant: **Dae-Young Kim**, Seoul (KR)
(72) Inventor: **Dae-Young Kim**, Seoul (KR)
(73) Assignee: **SPIGEN KOREA CO., LTD.**,
Bongeunsa-ro, Gangnam-gu, Seoul (KR)

(**) Term: **15 Years**

(21) Appl. No.: **29/575,833**

(22) Filed: **Aug. 29, 2016**

(51) LOC (11) Cl. **14-03**

(52) U.S. Cl.

USPC **D14/250**

(57) **CLAIM**

The ornamental design for a case for electronic devices, as shown and described.

DESCRIPTION

FIG. 1 is a front perspective view of a partially transparent case for electronic devices showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a three-dimensional view of the case with a support leg extended.

The broken lines in the drawings illustrate portions of the case for electronic devices and form no part of the claimed design.

1 Claim, 9 Drawing Sheets
